UNITED STATES PATENT OFFICE.

HARVEY DALZIEL, OF LONDON, ENGLAND.

METHOD OF INSURING THE ACCURATE REGISTRATION OF THE PLATES FOR MULTI-COLOR PRINTING.

1,296,929.

Specification of Letters Patent. Patented Mar. 11, 1919.

Application filed December 26, 1918. Serial No. 268,232.

To all whom it may concern:

Be it known that I, HARVEY DALZIEL, a subject of the King of Great Britain, residing at 2^a Plough Court, Fetter Lane, in the city of London, England, have invented a new and useful Improved Method for Insuring the Accurate Registration of the Plates for Multicolor Printing, of which the following is a specification.

10 It has already been proposed in order to facilitate the registration of the succeeding plates in multicolored printing to provide marks on each plate of the series where holes can be accurately drilled to fit on to pins correspondingly placed in the mounting board or bed.

15 The present invention deals with the registration of plates which represent a large number of subjects or a multiplication of the same subject.

20 There is no great difficulty in positioning a series of plates bearing only a limited number of subjects in such a manner that accurately registering printed products in different colors will result but the difficulty increases greatly as the number of the subjects on a sheet is multiplied.

25 Accordingly I take plates prepared by the ordinary photographic methods, or duplicates from same (if necessary) bearing the registering marks which indicate the positions where holes are to be drilled and with holes drilled in those positions.

30 From the plates, usually the first or yellow plates, I take a number of impressions on tracing paper equal to the number of subjects (or multiplications of one subject) which are to be represented on a single sheet. These impressions with printed side 35 downward are stuck on to a sheet of unshrinkable Manila paper or metal such as zinc in the positions required for printing purposes. The sheet is clamped on to an unshrinkable mounting board preferably of the kind patented in Great Britain by Parker No. 2168/04 and stretched evenly over it.

40 Through the registering marks I insert a fine bodkin pricking a hole into the board. 45 I then lift the Manila or metal sheet and

chalk a circle around each hole in the board to identify same for the positions for the steel pins, I then insert perfectly vertically fine steel pins of the exact size to fit the holes in the plate, using mechanical and other means to insure accuracy. I then drop the drilled plates of the first color on to the pins above mentioned. The holes in the plates are countersunk to enable them to find the pins more easily. The plates are then 55 screwed securely in their positions. The Manila sheet with transfers attached is then used again as often as necessary on other boards and sets of plates of the succeeding colors are similarly positioned thereon. 60 65

In the accompanying drawing I have illustrated the method of placing plates or blocks for multicolor printing in accordance with my invention.

70 Figure 1 is a plan view of a board partly covered by a sheet of unshrinkable material upon which a number of impressions from one of the plates are pasted.

Fig. 2 is an edge view of Fig. 1.

75 Fig. 3 is a plan view of a board with some of the plates fitted in position.

Fig. 4 is an edge view of Fig. 3.

80 Fig. 5 is a sectional view of a plate showing the counter sinking of one of the holes which enables its pin more readily to find its position.

85 *a* is a board, *b* is a sheet of unshrinkable material, *c* are impressions taken from one of the plates and stuck on to the sheet *b*. It will be observed that the impressions all bear marks *d* which are reproduced during the photographic reproduction of the picture in the way that is already understood. The sheet *b* having been clamped on to the board *a*, the impressions are pasted on to the sheet 90 in convenient positions. With a bodkin, awl or similar instrument pricks are made through the points *d* into the board. The sheet *b* is then turned back and the holes *e* (see Fig. 2) made by the awl are marked 95 with chalk or the like to identify them easily if there are other holes already in the board.

100 Pins *f* (see Fig. 4) are then inserted into the holes *e*, preferably driving them through holes in a flat plate or plates of the requisite

thickness to insure accuracy in direction and height.

Having got the pins in position for all the impressions the plates *g* previously drilled 5 at the points which print the marks *d* can be dropped on to the pins without difficulty especially if the noles are countersunk at the back as in Fig. 5. The plates are then finally secured.

10 The sheet is then clamped on to another board and the operation repeated.

A great number of plates, representing different subjects or duplicates of the same subject may thus be accurately positioned on 15 the several boards and all the boards being treated alike all the plates of the complete series are mounted on them with a certainty of their properly registering when the colors are superimposed in successive printings.

20 Thus the successive printings properly registered may be effected on separate letter press machines all at work at the same time with great advantages as to speed of production and with a minimum of danger arising

out of paper shrinkage between the printing 25 operations.

What I claim is:—

The improved method for insuring the accurate registration of a number of plates on mounting boards for multicolor printing, 30 which consists in taking from plates prepared by the usual processes and bearing registering marks, a number of impressions, fixing the impressions onto an unshrinkable sheet, clamping the sheet with the impressions thereon, onto a mounting board, marking the board through the sheet at the registration points, removing the sheet, inserting vertical pins at the points so marked, applying plates onto the pins and fixing the same 35 and repeating the application of the same sheet to other boards substantially as described.

In testimony that I claim the foregoing as my invention I have signed my name this 40 10th day of December, 1918.

HARVEY DALZIEL.
